UNITED STATES PATENT OFFICE.

FRANCIS T. ETHEREDGE, OF SOUTH NORFOLK, VIRGINIA, ASSIGNOR TO THE J. G. WILSON CORPORATION, OF NEW YORK, N. Y., A CORPORATION OF VIRGINIA.

FOLDING PARTITION.

Application filed September 26, 1925. Serial No. 58,698.

This invention relates to folding partitions or doors which slide along overhead on floor guideways or tracks.

As is well known to those skilled in the art, it is highly important that the doors of the folding partition when folded shall be held securely from movement in either direction along the guiding track or tracks. That is, the doors should be locked from movement along the tracks away from that side of the doorway adjacent to which the doors are folded and the doors should also be held firmly in spaced relation to each other.

15 The principal object of the present invention is to improve the construction and mode of operation of folding partitions and to provide novel and improved devices for holding the doors of such partitions from 20 movement along the tracks when the doors are folded.

With this object in view, the invention comprises certain novel and improved features, constructions and combinations of 25 parts hereinafter described and particularly pointed out in the claims, the advantages of which will be readily understood and appreciated by those skilled in the art.

The invention will be clearly understood 30 from the accompanying drawings illustrating the invention in its preferred form and the following detailed description of the construction therein shown.

In the drawings, 35 Figure 1 represents an unfolded six panel partition in front elevation;

Figure 2 is a horizontal cross-section through the partition when folded;

Figure 3 is a vertical section at right 40 angles to the ceiling track and the partition panel, showing an upper roller and spacing and locking means;

Figure 4 is a section through the ceiling track showing a panel in folded position;

45 Figure 5 is a horizontal section taken just below the ceiling track and showing part of the panels folded and part unfolded;

Figure 6 is a horizontal section through the ceiling track taken just above the rollers 50 and showing the panels in folded positions; and

Figure 7 is a view in front elevation partly in section showing the panels in folded positions.

55 As shown in the drawings, the partition

is divided into hinged doors or panel sections, each made up of two panels hinged together, the left hand panel of each section being shown at 1 and the right hand panel at 2. Panel 1 of the extreme left hand section is permanently anchored to the floor and ceiling and turns on the pivot pins 13 and 14 illustrated in Figures 1 and 7, while the panel 2 of said section is mounted for combined sliding and swinging movement along the tracks. Both panels of each of the remaining sections are mounted on the tracks for sliding and swinging movement. The right hand upper corner of panels 2 and the left hand upper corner of panels 1 (with the exception of panel 1 of the extreme left hand section) are provided with horizontal rollers 4 which run in the overhead track 3 and turn on the pivot bolts 5. The panels are provided at their lower outer corners with caster bolts carrying casters 5^a, which run on floor tracks 5^b, the bolts forming pivots for the panels.

The bolt 5 of the panel 1 of each section, except the extreme left hand section, is arranged to carry a locking dog for locking said panel from movement along the track, this bolt forming a pivot for the locking dog. Each of the bolts 5 which carries a locking dog is pivotally mounted in a frame 6 which is attached to the panel 1 as shown in Figure 3. A spring 7 connects the frame 6 with each of the bolts 5 and tends to rotate the bolt in a counter-clockwise direction when viewed from above as is shown in Figure 5.

A locking dog for locking each panel 2 is rigidly mounted on each of the rotatable bolts 5 and rotates with the bolt. This locking dog cooperates with a rack 9 which is mounted along the ceiling track and slightly below it and the rotation of the bolt 5 and locking dog 8 under the influence of the spring 7 tends to cause the dog to engage with the rack 9. In order to maintain the locking dog normally out of engagement with the rack 9 so that the sections may slide freely along the guide-ways, the frame 6 carries the pin or projection 10 which engages with the locking dog 8 when the panel is unfolded and forces the dog 8 out of engagement with the rack permitting the unfolded section to slide freely to the right.

Spacing plates 12, which are preferably of substantially rectangular shape, are loosely 110

mounted on the bolts 5 carried by the panels 2 of each section and are adapted to slide freely in the ceiling track 3. These spacing plates are arranged to engage at their ends the bolts 5 on the panels 1 in the manner shown in Figure 6 when the sections are folded to space the sections along the track. The dimensions of the spacing plates are so chosen that when the sections are folded the bolts 5 are kept a sufficient distance apart to maintain the folded panels at a predetermined distance apart at their side margins adjacent the track. The spacing plates 12 will space the upper parts of the several panels. A second set of spacing plates 11 may be attached at the middle or lower part of each of the panels 1 and are of such a shape that when the sections are folded they engage with the plates 15 on the panels 2 and space the lower portions of the panels. The plates 11 are preferably bent on an arc struck from the axis of the corresponding bolt 5. The operation of the auxiliary spacing plates 11 is shown in Figures 5 and 7. These plates are desirable where the height of the panels is great in order to maintain the lower portions of the panels in proper spaced relation.

The operation of the combined locking and spacing devices of the present invention is as follows: When it is desired to fold the partition shown in Figure 1, the left hand section is first folded and assumes the position shown in Figures 2 and 5. The central section is then slid along the tracks until the bolt 5 attached to the panel 1 of this section strikes against the spacing plate 12 mounted on the bolt 5 of the right hand panel 2 of the folded section. The central section is then folded. As the panel 1 of this section pivots about the bolt 5, the projection 10 moves laterally of the track and permits the dog 8 to engage the rack 9 after a comparatively small swinging movement of the panel, thus locking panel 1 against movement along the track toward the right (Fig. 5). On completing the folding of the section, the auxiliary plate 11 also engages with the plate 14 and maintains the alignment. The same procedure is then carried out with the right hand section, the completely folded panels being shown in section in Figure 2.

When it is desired to close the partition the reverse procedure is adopted and the right hand section is unfolded by grasping panel 2 thereof and pulling the same along the track. When the section is unfolded, a pin 10 on the panel 1 during the latter part of the unfolding movement engages the dog 8 and carries the dog out of engagement with the rack 9. As will be seen from Figure 5, the pin or projection 10 does not disengage the dog 8 from the rack 9 until the latter part of the movement of the pin so

that panel 1 is locked against movement along the tracks until the section is almost completely unfolded. When completely unfolded, however, the dog is released from the rack and the unfolded section can be slid along the track.

It will thus be seen that by means of the present invention the panels are locked against movement along the tracks toward the right (Figs. 2 and 5) almost as soon as any folding takes place and are not released until the section is again practically completely unfolded. At the same time, the spacing plates 12 and auxiliary plates 11 prevent motion toward the left and avoid the possibility of the panels striking each other during their folding or unfolding movement and thereby avoid the damage to the panels which sometimes occurs through the engagement of the panels with each other. Furthermore, the holding of the panels 1 firmly in position during the pivotal movement of the same results in a steady smooth swinging movement and enables the sections to be folded easily and quietly with comparatively little friction.

It is to be understood that the invention is not limited to the particular construction and arrangement of parts of the illustrated embodiment of the invention, but that the invention may be embodied in other forms within the scope of the claims.

Having explained the nature of the invention and having described the construction embodying the invention in its preferred form, what is claimed is:

1. In a folding partition, a series of separate sections each comprising two panels hinged together, a track on which the panels are mounted for sliding and swinging movement, spacing means for preventing the margins of the panels remote from the hinged edges from moving in one direction along the track when folded, and locking means actuated by the folding of the panels for preventing movement of certain of the panels in the opposite direction along the track when folded.

2. In a folding partition, a series of panels, a track on which the panels are mounted for sliding and swinging movement, spacing means for preventing the panels from moving in one direction along the track when folded, and locking dogs yieldingly connected with certain of said panels and thrown into operation during the folding movement of the panels for preventing movement of said panels in the opposite direction along the track when folded.

3. In a folding partition, a series of separate sections each comprising two panels hinged together, a track on which said panels are mounted for sliding and swinging movement, spacing devices mounted ad-

- 5 jacent the top of certain of said panels to space the margins of the same remote from the hinged edges when in folded position, and spacing devices mounted on certain of the panels below the top thereof to space the lower portions of the panels when folded.
- 10 4. In a folding partition, a series of separate sections each comprising two panels hinged together, a track on which the panels are mounted for sliding and swinging movement, spacing devices mounted adjacent the top of certain of said panels for spacing the margins of the same remote
- 15 15 from the hinged edges when in folded position, spacing devices mounted on certain of the panels below the top thereof for spacing the lower portions of said panels when folded, and locking means actuated by the folding of the panels for preventing movement of the panels in one direction along the track when folded.
- 20 5. In a folding partition, a series of panels, a track on which said panels are mounted for sliding and swinging movement, pivot bolts mounted on the panels and engaging in the track, spacing devices mounted on certain of the pivot bolts for
- 25 spacing the panels when folded, locking devices mounted on certain of the pivot bolts 30 and movable with relation to the corresponding panels, means located along the track to be engaged by said locking devices to lock the panels from movement in one direction along the track when in folded positions, means tending yieldingly to carry said locking devices into engagement with said means, and stops located on the respective panels for controlling said locking devices. 35
- 40 6. In a folding partition, a series of separate sections each comprising two panels hinged together, a track on which the panels are mounted for sliding and swinging movement, and means for spacing the panels when folded, comprising a spacing plate mounted on a panel of one section and curved in an arc substantially concentric with the arc of swinging movement of said panel and arranged to be engaged with the adjacent panel of the next previously folded section. 45
- 50 Signed at Norfolk, Virginia, this 18th day of September, 1925.

FRANCIS T. ETHEREDGE.
